UNITED STATES PATENT OFFICE.

EDWARD C. OSWALD, OF FULLERTON, PENNSYLVANIA.

SHOWER-BATH.

1,083,505.

Specification of Letters Patent.

Patented Jan. 6, 1914.

Application filed March 21, 1913. Serial No. 755,844.

To all whom it may concern:

Be it known that I, EDWARD C. OSWALD, a citizen of the United States, residing at Fullerton, in the county of Lehigh and 5 State of Pennsylvania, have invented certain new and useful Improvements in Shower-Baths, of which the following is a specification.

The present invention relates to shower 10 baths and the object of the invention resides in a device of simple construction, easy to apply and which is primarily intended for use in a bath tub.

My invention has the following advantages over other similar devices: It is very 15 easy to keep in order on account of the pipes used being straight, as all that is necessary is to remove the nipples on the end of the pipes and run a cleaning rod through. The 20 spray will reach the whole body at an even temperature and at a uniform pressure and is not localized, as is usual with other sprinklers. No curtain is required as with overhead showers and the water will not wet 25 the floor as would be the case if the curtain were not drawn together in the latter case. The dispensation of the curtain tends to cheapen the device considerably as does also the use of the straight pipes. The wa- 30 ter may be applied over the whole length of the body without wetting the hair, which is particularly appreciated by ladies. By turning the pipes while in the bath, the direction of the spray may be changed to dif- 35 ferent parts of the body and with the telescopic pipes, the spray may be directed high at one place and low at another, simultaneously. The telescopic feature also lends itself to localize the spray if desired, that

40 is the spray may be directed against the upper part of the body alone, or against the lower part alone by shortening the pipes. When shortened, the device is also best suited for bathing children and infants.

45 Lastly, the possibility of taking the shower bath in a reclining instead of a standing position is of great importance. The bather can therefore not slip on the bottom of the tub or fall down.

50 In the accompanying drawings representing my invention as applied to an ordinary bath tub with hot and cold water spigots Figure 1 shows a plan view of the sprinkler assembled. Fig. 2 in larger scale shows 55 the joint between the pipes. Fig. 3 a transverse section of a bath tub having

two water spigots with my device in position.

My shower bath consists principally of a pair of straight pipes A which are suspended 60 by means of carriers or hooks B from the top rim of a bath tub C. The pipes are provided with one, two or more straight rows of perforations or fine holes L confined within an angle of 30° to 45° along one 65 side of each tube. At the ends of the pipes nearest the foot of the bath tub, or where the spigots H, J are situated, I provide each pipe with a screwed on or otherwise connected nipple E so as to allow the pipe to 70 turn easily therein without causing leakage. The pipes A might be made in one piece or telescopic so as to be adjustable as regards length. In the latter case I provide an extension pipe A² which may be drawn in and 75 out relative to the main pipe A and also turned with regard thereto. This has the advantage that the spray may be localized and applied to one part of the body when so desired; and also that the spray may be 80 directed high to one part of the body and simultaneously low at another part. A small play of $\frac{1}{16}$ of an inch or so is allowed between the two pipes, and a collar A³ is provided on the inner end of the smaller 85 pipe and a stop and packing ring A⁴ at the outer end of the larger pipe, permitting easy turning and sliding between the pipes. Over the free ends of the sprinkler pipes are threaded or otherwise suitably secured 90 closing caps F.

For bath tubs having a hot water spigot H and a cold water spigot J, I provide a mixer or temperating member G. This mixer comprises a union with four branches, 95 two alined ones G², with hose connections G³ to the respective nipples E of the sprinkler; and two other branches G⁴ with hose connections G⁵ leading to the respective hot and cold water spigots H and J in the bath tub. 100 The branches G⁴ run out obliquely from the branches G².

The hooks B are S-shaped and each has an upper bend conforming to the rim of the tub. Its lower end slips easily over the 105 pipe and incloses it. One or more stops N is provided on the pipes. This for the purpose of preventing the pipes to be turned too far around and the spray coming over the bath room floor. The free end of each stop 110 may be turned over to form an eyelet and the stop could then serve the double pur-

pose of turning handle and stop. These stops may be made out of wire and riveted to the pipes.

I claim:—

- 5 In a portable shower bath the combination with a bath tub, of a sprinkler extending approximately the whole length of the tub and means for connecting the sprinkler to a water spigot, said sprinkler comprising a straight telescopic pipe provided with a plurality of perforations arranged in a plurality of rows along one side of the pipe, a space being formed between the cylindrical walls of the inner and outer members of

said telescopic pipe for the free circulation 15 of the water, said pipe being mounted to turn relative to said connecting means, whereby the spray from said pipe may be directed toward any part of the tub and stops on said pipe for limiting said turning, 20 said stops forming handles for turning said pipes.

In testimony whereof I affix my signature in presence of two witnesses.

EDWARD C. OSWALD.
